(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is an enlarged portion of the graphical user interface, enlarged to show detail.

The broken line showing a display screen or portion thereof with graphical user interface is included for the purpose of showing portions of the article which form no part of the claimed design.

1 Claim, 2 Drawing Sheets
